ATTORNEY

UNITED STATES PATENT OFFICE.

CHARLES H. WERT, OF NEWTON HAMILTON, PENNSYLVANIA.

WRENCH.

1,271,400.

Specification of Letters Patent.

Patented July 2, 1918.

Application filed May 19, 1917. Serial No. 169,698.

To all whom it may concern:

Be it known that I, CHARLES H. WERT, a citizen of the United States, residing at Newton Hamilton, in the county of Mifflin and State of Pennsylvania, have invented new and useful Improvements in Wrenches, of which the following is a specification.

This invention relates to wrenches and especially to wrenches of the quick action 10 type.

The object of the present invention is to provide a wrench of the above character in which the operating parts are arranged in a novel manner within the handle in order to 15 protect them from injury, the said parts being at the same time so constructed and positioned as to obviate the necessity of cutting away or weakening the shank beyond the handle, thereby adding to the strength 20 and usefulness of the wrench.

With these and other objects in view the invention consists of the following novel combination and arrangement of parts hereinafter more fully described, illustrated in 25 the accompanying drawings and pointed out in the appended claims.

In the drawings:—

Figure 1 is a side elevation of a wrench embodying the present invention;

Fig. 2 is an edge view of the same looking at the face of the rack bar;

Fig. 3 is a longitudinal central sectional view of the wrench; and

Fig. 4 is a cross section on the line 4—4 35 of Fig. 1.

Figs. 5 and 6 are detailed views illustrating the reversed pitch of the teeth of the rack bar and the reversed pitch of the teeth of the pawl for coöperation therewith.

Referring to the drawings in detail, like 40 characters of reference denote corresponding parts throughout the several views.

The wrench in the form shown includes a shank 10 upon one end of which is secured 45 the stationary jaw 11. The opposite end of the shank is secured within the socket of a handle 12, by means of screws or other fastening devices 13.

Slidably mounted upon the shank 10 is a 50 movable jaw 14, which is capable of being adjusted with respect to the jaw 11 by means of the novel mechanism hereinafter described.

Secured to one side of the jaw 14 is a bar 55 15, which operates within a groove 16 in one edge of a shank 10, the said groove be-

ing of sufficient length to permit the bar 15 to be moved therein to adjust the jaw 14 along the shank. The end of the bar 15 opposite the jaw 14 is provided with an inwardly turned angular extension 17, which is formed with an aperture 18 for the purpose of permitting its movement along the guide rod 19 carried by the handle 12. The handle is chambered as at 20 to provide for the movement of the extension 17 and between this extension and the end wall 21 of the chamber there is provided a spring 22. This spring surrounds the rod 19 and acts to normally close the jaws 11 and 14, 70 by forcing the jaw 14 in a direction toward the jaw 11.

The handle 12 is formed with a guide groove 23 to receive a bar 15, the said bar being provided with a finger piece 24, which 75 is located adjacent the extension 17 for the purpose of providing convenient means for adjusting the jaw 14. The finger piece 24 operates within a slot 25 formed in the handle 12 and connecting with the guide 80 grooves 23.

In order to hold the jaw 14 in its adjusted position the said jaw has secured thereto upon the side opposite the bar 15 a rack bar 26, which extends within a chamber 27 formed in the handle 12. The rack bar 26 is provided with three rows of transversely aligned teeth, the two outer rows 27 being pitched in a direction opposite to the inner or center row 28. Pivoted within the handle 90 12 is a dog 29, whose end 30 is located in the path of the teeth 27 and 28, in order to engage said teeth, and hold the jaw 14 in its adjusted position. The dog 29 is pivoted at 30 and is provided with a laterally-extending 95 finger piece 31, which extends through an opening 32 provided with a handle so as to be within convenient reach for the operation of the dog. The dog is normally forced into engagement with the teeth of the rack 100 bar by means of a spring 33, so that when it is desired to adjust the wrench it is necessary to press upon the finger piece 31 to release the dog. Upon the release of this dog the jaw 14 will immediately move in a direction 105 toward the jaw 11 under the action of the spring 22, so that the only operation necessary to position the wrench for use is the pressure upon the finger piece 31. In order to open the jaws the dog is raised and the jaw 110 14 moved in a direction away from the jaw 11 by means of the finger piece 24 and its bar

15. During this operation the spring 22 is placed under tension, so that the jaws 14 will be immediately closed by the release of the dog 29.
- 5 It is believed that the foregoing description, when taken in connection with the accompanying drawings will render the construction, operation and advantages of the invention clear to those skilled in the art.
- 10 The right is reserved to make such changes in the form and proportion thereof as will properly fall within the scope of the appended claims.

Having described the invention, what is
15 claimed, is:

1. A wrench comprising in combination a shank, a stationary jaw carried thereby, an adjustable jaw slidably mounted on said shank, a handle connected to the shank, re-
20 versely pitched rack teeth carried by the movable jaw, a dog pivoted to the handle, reversely pitched teeth also carried by said dog for engagement with the rack teeth car-

ried by the movable jaw to hold the latter against movement in either direction and 25 means located within the handle for urging the jaws to a closed position when the jaw holding means has been released.

2. A wrench comprising in combination a shank, a stationary jaw carried thereby, an 30 adjustable jaw slidably mounted on said shank, a handle connected to the shank, a rack bar connected at one end to said adjustable jaw and having its opposite end disposed within said handle, said bar being 35 provided with rows of reversely pitched teeth, a dog pivotally mounted in the handle and also provided with reversely pitched teeth having engagement with the teeth carried by the bar to hold the jaws against 40 movement in either direction and means located within the handle for urging the jaws to a closed position when the jaw holding means has been released.

In testimony whereof I affix my signature. 45
CHARLES H. WERT.
